UNITED STATES PATENT OFFICE

WILLIAM J. REGAN, OF WILKINSBURG, AND ENOCH GEORGE, JR., OF PITTSBURGH, PENNSYLVANIA, ASSIGNEES TO THE McCONWAY & TORLEY COMPANY, OF PITTSBURGH, PENNSYLVANIA, A CORPORATION OF PENNSYLVANIA

DRAFT APPLIANCE FOR RAILWAY CARS

Application filed February 27, 1928. Serial No. 257,320.

Our invention relates to draft appliances for railway cars and particularly to the provision of means for flexibly connecting the rear end of the coupler stem to a draft yoke by means of a key, the construction being such as to afford large bearing surfaces for the key and for the coupler in any positions the latter may occupy.

10 A further object of the invention is to provide a construction embodying a standard yoke, thus rendering possible employment, if desired, of a coupler having a standard shank or barrel whenever it may become necessary to replace the coupler.

15 The principal feature of the invention consists in connecting a car coupler with a slotted draft yoke by means of a key, a bearing block which is adapted to cooperate with a cushioning device being mounted in the yoke so as to move rearwardly with respect to the latter in buffing, the forward face of the bearing block and the rear end of the coupler stem having cooperating curved surfaces permitting the coupler to angle laterally with respect to the yoke, and the bearing block having forwardly extending portions which 20 overlappingly embrace opposite sides of the stem of the coupler whenever the latter moves longitudinally with respect to the block.

25 30 Other features of the invention, residing in advantageous forms of construction and particular relations of parts will hereinafter appear and be pointed out in the claim.

35 In the drawings, illustrating preferred embodiments of the invention:

Figure 1 is a view, partly in plan and partly in horizontal section, of a portion of a railway draft appliance constructed in accordance with the invention, the head of the car coupler and the rear portion of the yoke being omitted.

40 45 Figure 2 is a view, partly in vertical section and partly in elevation, of the construction shown in Figure 1, the relation of the cushioning device to the mechanism being diagrammatically illustrated by dot and dash lines.

50 Figure 3 is a view corresponding to Figure 1 but illustrating a modified form of the invention employing a horizontal yoke and

wherein the rear bearing block is integrally united to the forward follower of the draft gear.

Figure 4 is a view partly in vertical section and partly in elevation, of the construction shown in Figure 3.

In the drawings, 1 indicates the stem of a car coupler provided at its rear end with a slot 2 for receiving a transversely extending key 3 by which the coupler is connected to the draft yoke 4 in a well known manner. The yoke, which has vertically spaced arms 5 for receiving a cushioning unit, as shown diagrammatically at 6 in Figure 2, is preferably of the present American Railway Association standard design, being formed at its forward end with key slots 7 of sufficient length to permit the coupler to travel rearwardly with respect to the yoke in buffing.

At its rear end the stem of the coupler is formed with a cylindrically curved surface 8 which cooperates with the correspondingly curved surface 9 of a bearing block 10 disposed between the end of the coupler shank and the cushioning unit, a large bearing area thus being provided for transmitting buffing shocks to the cushioning unit in any angularly displaced position the coupler may occupy. The block 10 is floatingly mounted in the draft yoke and is provided with forwardly extending portions 11 which overlappingly embrace opposite sides of the coupler stem 1 when the parts are in normal position. The forward extensions 11, whose outer faces 12 are preferably inclined so as to converge forwardly in conformity to adjacent inclined surfaces 13 of the yoke, serve as guides to insure the return of the bearing block 10 to proper position in the event it should float rearwardly against the forward follower or draft gear when the coupler and yoke move outwardly under draft. The curved surface 9 of the floating bearing block extends in advance of the rear ends of the key slots 7 in the yoke when the parts are in normal position, ample bearing area thus being afforded for the coupler, and the parts being enabled to be made sufficiently strong while at the same time of such dimensions as will permit the substitution of a coupler hav-

ing a standard shank or barrel in place of the special design of coupler and bearing block when the latter are not available.

In advance of the curved bearing surface 5 and concentric therewith, the coupler shank 1 is fashioned on its interior with a curved bearing surface 14 cooperating with a correspondingly curved surface 15 on the rear side of a key seat member 16, the center of curvature of the several curved surfaces preferably being located approximately at the back edge of the transverse key 3 or slightly rearwardly thereof in order to allow the coupler to swing laterally through a considerable range without interfering with the ends of the key seat member 16. To permit the key seat member to be assembled with the coupler the key slot 2 in the shank of the latter is widened at its rear end, as indicated at 17. The forward 20 face of the key seat member is formed with a groove or channel 18 corresponding in form to the rear edge of the key and into which the latter extends. By this means the connecting key 3 is enabled at all times when the 25 coupler is subjected to draft to have full bearing on the yoke 4 and against the key seat member 16.

To assemble the construction shown in Figures 1 and 2, the bearing block 10 at the rear 30 of the coupler shank is inserted between the arms 5 of the yoke and pushed forward into the hooded rectangular section of the yoke. The draft gear or cushioning unit is then placed in the yoke and these assembled parts 35 are raised to place between the sills of the car. The key seat member or pivoted block 16 is then inserted through the enlarged portion 17 of the coupler key slot 2 and moved rearwardly until its curved bearing surface 40 15 comes into engagement with the correspondingly curved surface 14 of the coupler. The coupler and the key seat member 16 are then assembled with the yoke 4 in position on the car and the draft key 3 is inserted in the 45 slots 2 and 7 of the coupler and yoke respectively.

In the form of the invention illustrated in Figures 3 and 4, the yoke 19 is of the horizontal type, its arms 20 being in transverse alignment. At its forward end the yoke is formed with slots 21 for receiving a transversely extending key 22 serving to connect the yoke to the coupler in a well known manner, the key preferably being of standard 55 form and the key slots 21 of the yoke extending rearwardly sufficiently far to permit the coupler to move with respect to the yoke for the full extent of its buffing travel. To the rear of the key slots 21 the arms 20 of the 60 yoke are provided with oppositely disposed slots 23 corresponding in length to the slots 21 and adapted to receive a transversely disposed key which extends through the slot 24 in a follower 25 positioned to the rear of the 65 car coupler.

The key (not shown) which extends through the slots 23 and 24 as well as through elongated slots in the draft sills of the car serves, in a well known manner, to limit forward movement of the follower 25 when the 70 coupler is subjected to draft forces. This key, like the key 22, is preferably of standard form.

At its front end the follower 25, which will be recognized by those skilled in the art as of the Farlow type, is formed with a bearing block portion 26 having a forwardly facing cylindrically curved surface 27 with which the correspondingly curved rear end 8 of the coupler stem 1 cooperates in buffing, the curved face 27 being preferably positioned in the same manner as the bearing face 14 heretofore described. The bearing block portion 26 has forward extensions 28 which overlappingly embrace opposite sides of the stem 80 of the coupler so as to form guides insuring the proper operative relation of the coupler and bearing block. The coupler 1 and key seat member 16 employed in this construction are preferably of the same form as heretofore described and accordingly their structural features have been indicated by corresponding reference numerals.

We claim:

In a draft rigging, the combination with 95 a coupler; of a yoke having a hooded forward section, defined in part by upper and lower walls; a shock absorbing device having front follower acting means; and means detachable from the yoke occupying each of the spaces defined by the front face of said follower acting means, top or bottom wall of the hood section, and corresponding opposed surface of the butt end of the coupler shank, said removable means being held in 100 relatively spaced relation by said follower.

In testimony whereof they affix their signatures.

WILLIAM J. REGAN.
